NESTABLE CUP

Harold Edward Taylor, Garforth, Leeds, England, assignor to Plastona (John Waddington), Ltd., Leeds, England

Filed Jan. 6, 1975, Ser. No. 538,929

Term of patent 14 years

Int. Cl. D9—03

U.S. Cl. D9—220

FIG. 1

FIG. 2

FIG. 3

FIG. 4

FIG. 5

FIG. 1 is a perspective view of a nestable cup embodying my new design;

FIG. 2 is a side elevational view;

FIG. 3 is a top plan view;

FIG. 4 is an enlarged, fragmentary, elevational view in cross-section, taken along the plane 4—4 of FIG. 3 showing the uppermost portion of the cup; and

FIG. 5 is an enlarged, fragmentary, elevational view in cross-section taken along the plane 4—4 of FIG. 3 showing the lowermost portion of the cup.

I claim:

The ornamental design for a nestable cup, as shown.
